US0D1096825S

(12) **United States Design Patent** (10) Patent No.: **US D1,096,825 S**
Martinez Galan (45) Date of Patent: ** Oct. 7, 2025

(54) **DISPLAY SCREEN OR PORTION THEREOF WITH A GRAPHICAL USER INTERFACE**

(71) Applicant: **Stryker Corporation**, Kalamazoo, MI (US)

(72) Inventor: **Jose Daniel Martinez Galan**, Seattle, WA (US)

(73) Assignee: **Stryker Corporation**, Portage, MI (US)

(**) Term: **15 Years**

(21) Appl. No.: **29/872,164**

(22) Filed: **Mar. 7, 2023**
